FINGER RING OR SIMILAR ARTICLE

Ruth W. Shuckra, 34 Tuttle St., Saugus, Mass.

Filed Aug. 31, 1960, Ser. No. 61,963

Term of patent 14 years

(Cl. D45—10)

Fig. 4

Fig. 2

Fig. 1

Fig. 3

Fig. 5

Fig. 1 is a front view of a finger ring or similar article showing my new design;

Fig. 2 is a side elevation looking from the left of Fig. 1 and with a portion of the band of the ring broken away for convenience of illustration;

Fig. 3 is a side elevation looking from the right of Fig. 1 with a portion of the band of the ring broken away for convenience of illustration;

Fig. 4 is a top view; and

Fig. 5 is a bottom view.

I claim:

The ornamental design for a finger ring or similar article, substantially as shown and described.
